ATTORNEY.

UNITED STATES PATENT OFFICE.

PETER G. KLUSE, OF LOS ANGELES, CALIFORNIA.

AEROPLANE.

Application filed February 29, 1928. Serial No. 253,115.

This invention relates to an improved construction and control mechanism for flying machines of the heavier than air type.

Broadly considered, among other features, 5 the invention comprises an aeroplane having an elongated casing provided with longitudinally extending partitions to form with said casing a plurality of superposed air containing chambers, in combination with 10 means for entraining air into said chambers through the casing wall for the purpose of directing the currents of air thus formed in such a manner as both to stabilize the machine and control the altitude and propuls- 15 ion thereof.

Among the objects of the invention are to produce an aeroplane having greater lifting power, greater carrying power, greater stability, and more evenness in running, and 20 in general safer and more efficient control.

A particular advantage secured by this invention is the provision of improved means for safely and efficiently retarding the speed preparatory to making a landing.

25 Other objects and advantages may hereinafter appear.

The invention consists in the various parts, combinations of parts, and the details of construction hereinafter described and 30 then more particularly pointed out in the claims.

Referring to the accompanying drawings, which illustrate a preferred embodiment of the invention,

35 Figure 1 is a vertical mid-section of the complete machine.

Figure 2 is a view partly in plan and partly in section, the sectioned portion being on line 2—2 of Figure 1.

40 Figure 3 is a vertical section on line 3—3 of Figure 1.

Referring in detail to the drawings, within the elongated main casing 5 is a longitudinally extending horizontal upper partition 6 and a like lower partition 7, these partitions 6 and 7 dividing the main chamber into a plurality of superposed longitudi- 45 nal chambers, namely the main central chamber 8, upper auxiliary chamber 9 and lower auxiliary chamber 10. The auxiliary chambers 9 and 10 increase in cross section toward the front end of the machine. Within said main chamber 8 is to be stored freight for shipment and this chamber also 50 will be equipped to accommodate passengers.

55 Referring now to the means for stabiliz-

ing the machine and directing its movements, through the top wall of the main casing 5 are provided a series of air openings 15, each of said openings being provided with valves 16 for regulating the size thereof. By preference and as shown in Figure 1, each of said valves consists of a flap secured to the casing near the front edge of the opening 15 which it controls, said valves 16 inclining more or less toward the stern of the ship, their inclinations being controlled by control wires 17. The bottom of the machine is likewise provided with a series of openings 18 guarded by the valves 19 having control wires 20. Springs 17^a oppose control wires 17, and springs 18^a oppose control wires 20.

Referring now to the propellers and means for operating same, 25 designates the 75 main propeller of usual construction and location, which is secured to shaft 26 driven by a motor 27. By this invention are provided a forward auxiliary propeller 29 and a rear auxiliary propeller 30, said propellers being 80 provided on a common driving shaft 31 driven by a motor 32. Rear propeller 30 is fixed to shaft 31 and front propeller 29 rotates with said shaft only when clutch 26^a is in operation. Clutch 26^a is operated by 85 control wire 26^b. A partition 35 separates these two auxiliary propellers.

A current control air chamber 37 is provided with upper and lower continuously open apertures 38 and 39 which respectively 90 communicate with the upper auxiliary chamber 9 and the lower auxiliary chamber 10. After being drawn in through said apertures 38 and 39 the air is expelled through the side openings 8^a (see Figure 2). 95 Through the partition 35 is provided an upper air port 40 controlled by a valve 41 and a lower air port 42 controlled by a valve 43. 41^a and 43^a are the controls for these valves. At the front end of the machine just back of 100 the main propeller are located a circular series of apertures 45. 51 designates the main rudder.

The machine may be provided with any desired landing gear, the drawings showing 105 a front under carriage 60 and rear skid 61. The rear skid must support the rear portion of the main casing at a sufficient height to prevent the relatively large rudder 51 from being injured by contact with the ground 110 during alighting or starting.

Operation: Preparatory to beginning a

flight, the rear auxiliary propeller 30 is put into operation, the valves 41 and 43 being maintained closed, and the valves 19 beneath the lower auxiliary chamber 10 also being closed. Under these circumstances the operation of said propeller 30 entrains air through the upper ports 15 and expels it through the side opening 8^a near the front end of the machine just in advance of the main wings at the same time directing the air back against these wings. The effect of this operation will be to lighten the machine considerably. When this has been accomplished the main propeller 25 is put into operation, thus driving the machine forwardly and quickly securing a take-off. During the flight the upper valves 16 are closed and the lower valves 19 opened when it is desired to descend quickly to a lower level, and the quick ascension to a higher level is aided by opening the upper valves 16 and closing the lower valves 19, the latter operation being always performed when it is desired to descend quickly for landing. When it is desired suddenly to check the speed of the machine for alighting or for any other purpose, the clutch 26^a is operated to put in action the front auxiliary propeller 29 which entrains air from auxiliary chambers 9 and 10 through the ports 38 and 42 and ejects the air from the row of front ports 45.

I claim:

1. In an aeroplane, an elongated casing having a plurality of superposed longitudinally extending air chambers, the uppermost of said chambers having air openings through the top of the casing, and a propeller adapted to entrain air through said openings, direct it toward the front of the casing and then discharge it in a rearward direction through the sides of the casing.

2. In an aeroplane, an elongated casing having a plurality of longitudinally extending superposed air chambers, the uppermost of said chambers having apertures through the top wall of the casing, rearwardly inclined shutters located on top of said casing adjacent the front edges of said apertures, means for entraining air through said

apertures directing it toward the front end of the interior of said casing and then directing it rearwardly and outwardly through apertures in said casing.

3. In an aeroplane an elongated casing, a transverse partition within said casing to form a relatively narrow upper longitudinally extending chamber therein, said partition at its rear end uniting with the top wall of said casing and at its front end being spaced away from said top wall to form an air opening, there being a plurality of openings through the top wall of said casing, and a propeller adapted to entrain air through said top openings, draw it forward over the front end of said partition and then force it outwardly and rearwardly through openings in the casing.

4. In an aeroplane, a casing having a main elongated air chamber, an elongated auxiliary air chamber thereabove, an elongated auxiliary air chamber therebeneath, the front ends of said auxiliary chambers being open and the front end of said main chamber being closed adjacent to the open ends of said auxiliary chambers, said casing having an air discharge opening at its mid height at each side located near the open front ends of said auxiliary chambers and adapted to discharge air outwardly and rearwardly, the upper auxiliary chamber having top air inlets and the lower auxiliary chamber having bottom air inlets, and a propeller to entrain air through the air openings of both of said auxiliary chambers, withdraw it from their open front ends and then discharge it from said side openings of the casing.

5. In an aeroplane, the combination, with a hull or casing having apertures in its front end and a main propeller mounted in front of said apertures; of an auxiliary propeller mounted rearwardly of said apertures and means to drive said auxiliary propeller in a direction to force through said openings a current of air to oppose the air current created by said main propeller when it is desired to check the speed of the aeroplane.

In testimony whereof I affix my signature.

PETER G. KLUSE.
